(57) **CLAIM**

The ornamental design for a furnace cabinet panel, as shown and described.

DESCRIPTION

FIG. 1 is a perspective view of a furnace cabinet panel showing our new design;

FIG. 2 is a top view thereof;

FIG. 3 is a front view thereof; and,

FIG. 4 is a left side view thereof, the right side view being a mirror image thereof.

The broken line showing of additional structure of a furnace in FIG. 1 is for environmental purposes only and forms no part of the claimed design.

1 Claim, 2 Drawing Sheets

FIG. 1

FIG. 2

FIG. 3

FIG. 4
